UNITED STATES PATENT OFFICE.

BENJAMIN I. CHURCH, OF TRAVERSE CITY, MICHIGAN.

ROAD-DRAG.

1,191,155.

Specification of Letters Patent. Patented July 18, 1916.

Application filed June 22, 1914. Serial No. 846,637.

To all whom it may concern:

Be it known that I, BENJAMIN I. CHURCH, a citizen of the United States, residing at Traverse City, in the county of Grand 5 Traverse, State of Michigan, have invented certain new and useful Improvements in Road-Drags; and I do hereby declare the following to be a full, clear, and exact description of the invention, such as will 10 enable others skilled in the art to which it appertains to make and use the same.

This invention relates to improvements in road machines, and particularly to drags for scraping and smoothing the surface of the 15 road.

The principal object of the invention is to provide a simple device of this character which will effectively scrape and smooth the surface of the road and which will conform 20 to the water shed contour of the road bed.

Other objects and advantages will be apparent from the following description, when taken in connection with the accompanying drawings.

25 In the drawings: Figure 1 is a plan view of a drag made in accordance with my invention. Fig. 2 is a side elevation. Fig. 3 is a rear elevation. Fig. 4 is an enlarged sectional detail on the line 4—4 of Fig. 1.

30 Referring particularly to the accompanying drawings, 10 represents a plurality of parallel and longitudinally arranged drag bars which are joined together at their ends and at intermediate points by the links 11, 35 these links being loosely connected with the beams. Secured to the under face of each of the bars is a plurality of laterally extending and obliquely arranged strips 12, each of which is provided with a metal shoe 13 for scraping contact with the road surface. 40 These strips 12 extend from the sides of the bars in alternate relation and in opposite di-

rections. As clearly shown, each of the bars is provided with a series of these strips, the outer ends of the strips of each bar being 45 disposed behind those of the adjacent bar. The forward ends of the bars are connected to a transverse draft beam 14 by means of the chains 15, which beam carries a draft evener 16.

50 By this arrangement, the bars will adjust themselves to the transverse curvature of the road, and thus scrape the road in a more efficient manner than the rigid drags heretofore provided. The rigid drag has a tendency to flatten the road bed in places which destroys the water shedding contour of the road and permits ruts and shallow places to form which will fill up with water and destroy the contour of the road.

55 What is claimed is:

A road drag comprising a plurality of longitudinal parallel drag bars, flexible connections between the members, a transverse draft beam disposed at one end of the said 65 members, flexible connections between the beam and the forward ends of the bars, and removably mounted transversely extending road engaging scraping elements carried by the drag bars and extending obliquely to the 70 line of movement thereof, the outer ends of the said scraping elements of each drag bar extending beyond the opposite sides of the bar in alternate opposite relation, and between the scraping elements of the adjacent 75 bars, the scraping elements of certain of the bars extending obliquely opposite to those of the other bars.

In testimony whereof, I affix my signature, in the presence of two witnesses.

BENJAMIN I. CHURCH.
